UNITED STATES PATENT OFFICE

BERNARD CURLIN, OF TOLEDO, OHIO

CIGAR LIGHTER

Application filed June 16, 1928. Serial No. 285,802.

This invention relates to portable cigar lighters.

This invention has utility when incorporated in lighters embodying a pyrophoric alloy and an abrader to coat therewith, and is especially adapted for lighters of pocket size.

Referring to the drawings:

Fig. 1 is a side elevation of the lighter.

Fig. 2 is an end elevation of the device looking from the right side of Fig. 1.

Fig. 3 is a side elevation of the device with the cap removed.

Fig. 4 is an end elevation of the device looking from the right of Fig. 3.

Fig. 5 is an enlarged view on the line V—V, of Fig. 4.

Fig. 6 is a view on the line VI—VI of Fig. 5.

Fig. 7 is a view on the line VII—VII of Fig. 2, showing the coaction between the alloy and the abrader therefor.

Fig. 8 is an enlarged view of the abrader head.

The tubular casing 1 has open end 2 and closed end 3. Adjacent the closed end 3 the tubular casing has interior tapered seat 4. The casing 1 is of a material being non-conductive to heat.

Interfitting with the casing 1 through the open end 2 thereof, is second tubular member 5 provided with open end 6 coacting with the tapered seat 4 for frictional assembly between the members 1 and 5 in telescopic relation and seating tight against the tapered seat 4. Remote from the open end 6 the tubular member 5 has reduced portion or neck 7 terminating in open end 8.

Mounted in the open end 8 as a partial closure therefor is the plug 9, constituting a burner tip. The plug 9 is flattened at one or both sides and is provided with groove 10 thereabout. This coacts with inwardly projecting offsets 11, being prick marks, of the tubular member 5 providing a bayonet joint means for locking the plug in the open end 8 and permitting ready removal thereof. A shoulder 12 of the plug 9 serves as positioning means for the neck 7 of the reservoir on the burner tip member 5.

Mounted centrally of the neck 7 and hav-

ing press fit therewith is scratch pin 15 extending outwardly therefrom to convex portion 14 terminating in flat circular end 15 with a sharp scratching edge, at the junction of the convex portion 14 and the flat end 55 face 15.

The plug 9 has the flat sides 17 forming wick openings 18 in the burner tip, through which asbestos wicks 19 extend from the fuel reservoir or interior portion 20 of the tubular member 5. Packed about for contact with the wick in the reservoir 20 is fuel retaining fibrous material 21 usually absorbent cotton.

The plug 9 is provided with well 22 about the pin 15, the wick 19 completing the well 60 wall and such wick terminating adjacent thereto.

Cap 23 is formed to telescopically fit over the exposed portion of the tube 5 for completing a cylindrical body. The cap 23 is 70 provided with transverse seat 24 terminally thereof in which is disposed clip 25 carrying pyrophoric alloy block 26. The clip 25 has a projection 27 formed by a punch prick coacting with depression 28 in the seat 24 in 75 cap 23 for snap coaction therewith permitting removable assembly as to the cap.

In creating a flame, the cap 23 is removed from the lighter, exposing the abrader or pin 15 and the abrader then has its cutting edge 16 struck or scratched along the exposed face of the pyrophoric alloy block creating sparks which are thrown against the wick terminals and also into the well 22. The well 22 provides a fume retaining means fed from the reservoir 20 by the wicks. The well is notched by the flat formation opposite the wick which insures the filling of the well with vapor.

A single wick may be used, doubled upon itself to have both its ends terminate adjacent the well and the abrader. The abrader may be readily removed in case such becomes damaged due to dropping the lighter or breakage of the pin. Fuel replenishment is 90 easily accomplished by removal of the casing 1 from the tube 5 exposing the open end 6 thereof into which the fuel may be poured about half full. Upon replacement of the casing 1 it is held against working loose and 95 100

a tight joint is secured by the coaction of the tapered seat 4 with the tube end 6. The material from which the casing 1 and the cap 23 are constructed is non-conductive of heat, as casein, hard rubber, or fiber, thereby maintaining fuel evaporation at a minimum. This has special utility in pocket carried lighters in maintaining the fuel cool by insulation from body-heat.

10 The parts are easily produced and quickly assembled, and any damaged part may be manually replaced. The pyrophoric alloy is quickly resurfaced. The device when covered presents a small, neat, cylindrical unit 15 conveniently carried in the pocket and quickly brought into use. The casing material may be a pheno-condensation product and variously colored thereby adding to the appearance of the lighter. The abrader being 20 carried by the reservoir insures fumes about the wick and proper wick spacing as to the abrader is maintained, and burning may be had to the full extent of fuel in the reservoir.

Having thus described my invention, what 25 I claim as new and desire to secure by Letters Patent, is:

1. In a lighter, the combination of an open ended tubular reservoir with a burner tip, a plug with flattened sides disposed in the said 30 burner tip to form wick passages, the said plug having a depression or well at its center communicating with the wick passages, and a central scratcher pin carried by the said plug.

2. In a lighter, the combination of an open 35 ended tubular reservoir with a burner tip, a plug with flattened sides disposed in the said burner tip to form wick passages, the said plug having a depression or well at its center, and a scratcher pin carried by the said 40 plug.

3. In a lighter, the combination of a reservoir with a burner tip and a scratcher pin, a telescopic cap with a transverse dovetail recess seat, a removable clip in said seat provided with an engaging projection, and a pyrophoric block in said clip on said cap, as 45 specified.

4. In a lighter, a scratcher pin with a flat head and with a convex under meeting surface forming a sharp edge, and a recurved back surface to the body of pin.

5. In a lighter, a reservoir with a reduced end formed into a burner tip, a scratcher pin block in said tip with a central well and flat 55 sides to form wick spaces at each side of said well, wicks in said spaces extending above said well, a scratcher pin with a flat head and having a convex under meeting surface forming a sharp edge, and a recurved back surface to the body of the pin.

6. In a lighter, a tubular fuel reservoir having a wick end and an open end, a wick retainer having two parallel flat sides and detachably connected to said wick end, a wick adjacent each side, an abrading device

secured to said wick retainer between said wicks, a base engaging the sides of said reservoir and sealing the open end thereof, and a cover fitting over said wick and abrading device and carrying pyrophoric material to be engaged by said abrading device secured to said wick retainer.

7. In a lighter, a tubular fuel reservoir having a wick end and an open end, a wick retainer in said wick end, detachably secured thereto, a wick therein, an abrading device adjacent said wick, a base frictionally engaging the sides of said reservoir and sealing the open end thereof, and a cover fitting over said wick and abrading device and frictionally engaging said reservoir and carrying pyrophoric material to be engaged by said abrading device.

8. In a lighter, a tubular fuel reservoir having a wick end and an open end, a wick retainer having two flat sides and detachably connected to said wick end, a wick adjacent each side, and abrading device between said wicks, a base frictionally engaging the sides of said reservoir and sealing the open end thereof, and a cover fitting over said wick and abrading device and frictionally engaging said reservoir and carrying pyrophoric material to be engaged by said abrading device.

9. In witness whereof I have hereunto set my hand.

BERNARD CURLIN.
